UNITED STATES PATENT OFFICE.

ARTHUR J. BRIGGS, OF SYRACUSE, NEW YORK, ASSIGNOR TO REMINGTON TYPE-WRITER COMPANY, OF ILION, NEW YORK, A CORPORATION OF NEW YORK.

TYPE-WRITING MACHINE.

1,147,299.

Specification of Letters Patent. Patented July 20, 1915.

Application filed September 25, 1913. Serial No. 791,734.

To all whom it may concern:

Be it known that I, ARTHUR J. BRIGGS, citizen of the United States, and resident of Syracuse, in the county of Onondaga, 5 and State of New York, have invented certain new and useful Improvements in Type-Writing Machines, of which the following is a specification.

My invention relates to typewriting machines and more particularly to case shift mechanism for such machines.

It is practicable with but two types on a bar to effect a relative case shift movement between the platen and type bars with 15 the aid of ordinary parallel links. However, when a greater number of types, say three, are provided on each bar, it is impracticable to use ordinary parallel links to guide the shifted part. This is due to 20 the fact that the platen, or the shifted part, swings in an arc at the printing point resulting in a difference in the extent of angular movement through which the type bars must move to the printing point in different 25 case positions of the platen or shifted element. This would render it necessary, in order to avoid throwing most, if not all, of the types "off their feet", to make the types so that the printing faces on each bar would 30 be in a plane or planes different from the plane or planes of the type faces on every other bar, which would be impracticable from a manufacturing point of view.

One of the main objects of my invention, 35 generally stated, is to overcome these disadvantages and to provide a simple and efficient linkage which will guide the platen, or shifted part; so as to effect a straight line movement at the printing point; so 40 that all of the type bars have the same extent of angular movement to the printing point in the different "case" positions of the parts; so that the printing faces on all of the type bars may be made in a like 45 manner; so that it is rendered practicable to make the type faces on each bar in the same plane or substantially the same plane; and so that the construction will aid materially in the production of a simple and efficient typewriting machine which may be manufactured at small cost.

To the above and other ends which will hereinafter appear, my invention consists in the features of construction, arrange-

ments of parts and combinations of devices 55 set forth in the following description and particularly pointed out in the appended claims.

In the accompanying drawings, wherein like reference characters indicate corresponding parts in the various views, Figure 1 is a vertical, fore and aft, sectional view of sufficient number of parts of one form of typewriting machine to illustrate my invention in its embodiment therein; parts 60 being represented in the normal position for printing lower case characters. Fig. 2 is a fragmentary rear elevation of a portion of the same. Fig. 3 is a fragmentary skeleton view, with portions in side elevation and 65 portions in section, of the case shifting mechanism and some of the associated parts; the view showing the parts as they appear for writing "figures" and other "upper case" characters. Fig. 4 is a like view of the 70 same but showing the parts as they appear for writing "capitals" and other "upper case" characters. Fig. 5 is a diagrammatic view illustrating the different positions 75 parts of the case shifting mechanism as 80 assume when the platen is in different writing or "case" positions. Fig. 6 is a fragmentary, detail, vertical, fore and aft, sectional view showing the means for locking either 85 case shift key in the actuated position, the view also illustrating some of the associated parts. Fig. 7 is an enlarged side view of 90 a type block.

I have shown my invention embodied in the present instance in a front-strike 90 double shift machine, the frame of which comprises side plates 1 united by a front cross plate 2, by a keyboard 3 and by a cross plate 4, the latter also constituting 95 a type bar segment. A series of segmentally arranged type bars 5 are pivoted at 6 to move upwardly and rearwardly to the printing position. The type bars are mounted on hangers (not shown) on the type bar segment 4, the pivots of the type bars being 100 disposed in an inclined plane as indicated in Fig. 3. Each type bar, in the present instance, is provided with three types 7, 8 and 9. The type bars are actuated by suitable key controlled actuating devices (not 105 shown) operative on pull links 10 which are connected at their rear ends to the type bars.

The types are adapted to impact against the front face of a cylindrical platen 11 mounted on a shaft 12 which is received in bearing openings in end plates 13 of a carriage. These end plates are fixed to and extend upwardly from a traverse or guide bar 14 formed so as to provide oppositely grooved bearings 15 for the reception of anti-friction balls or rollers 16. The forward set of anti-friction rollers is likewise received in a ball race or track 17 of a shift bar, rail or frame 18. A plate 19 is formed with a grooved guide way 20 to receive the rear set of anti-friction balls 16, the plate being secured to the shift bar by screws 21.

The carriage, comprising the member 14 and the end plates 13 united by a tie rod 13^a and carrying the platen 11, is thus mounted to travel from side to side of the machine 20 on the shift rail, bar or frame 18 and is shiftable with the latter in the case shifting movements thereof.

The parts are mounted for case shifting movements in the following manner: A pair 25 of relatively long parallel links 22 is normally substantially horizontally disposed as shown in Figs. 1 and 5. The rear end of each link 22 is pivoted, as at 23, to a side plate 1 of the frame of the machine. Each 30 link 22 is therefore pivoted to turn on a fixed center at its rear end. The forward end of each link is pivoted at 24 to the shift rail or frame 18, the point of pivotal connection of each link describing an arc of which 35 the pivot 23 is a center. Beneath the parallel links 22 is a second pair of relatively short parallel links 25, each of which is pivoted at its rear end to the frame of the machine, as at 26. The forward end of each 40 of the links 25 is pivoted, as at 27, to a depending arm 28 which forms part of the shift bar or frame 18. It will be understood, therefore, that each link 25 turns on a fixed center 26 and describes an arc around said 45 center at its point of pivotal connection 27 with the shift rail. It will be seen that the links 25 are shorter than the links 22 and normally extend at an angle thereto, although both sets of links in the present instance are directed fore and aft of the machine. It will also be understood, from a comparison of Figs. 1, 3 and 4, and from an inspection of Fig. 5, that the angular relation of the relatively short and long links 55 varies during case shift movements of the parts, and that the two sets of links are brought into parallelism, or substantial parallelism, when the platen attains a given position intermediate the two extreme case 60 shifted positions thereof. The purpose of this linkage for guiding and controlling the platen in its case shift movements is to effect a straight line movement of the platen at the printing point in the shifting movement of the latter to its different case posi-

tions, or to bring the printing points in all three positions in a straight line as will hereinafter more clearly appear.

It will be understood that the platen is normally in the lowermost position represented in Fig. 1 and is shifted in one direction from this position to a plurality of different case positions, as indicated in Figs. 3 and 4. When the platen is in the lowermost position shown in Fig. 1 the "lower" 70 case" types 7 are adapted to impact at the printing point, whereas the types 9 carrying the "figures" and other "upper case" characters are adapted to impact at the printing point when the platen is in the highest position represented in Fig. 3. When the platen is shifted to the position shown in Fig. 4 the intermediate types 8 on the type bars, which are for "capitals" or other "upper case" characters, are adapted 80 to strike at the printing point.

Means for effecting the relative case shifting movements between the platen and printing instrumentalities, are shown in the present instance comprising two levers 29 and 30 90 arranged side by side and pivoted to the left-hand side plate of the frame on pivot screws 31 and 32, respectively, the pivots for these levers being arranged at different points fore and aft of the machine. Each 95 lever extends rearwardly beyond its pivot and projects beneath a pin 33, which projects laterally from one of the depending arms 28 of the shift bar or frame. Each of these levers is a lever of the first order 100 and extends forwardly to the keyboard of the machine where it is pivotally connected, as at 34, with a key stem 35 which extends through a guide opening in the keyboard plate 3 and is provided at its upper end 105 with a finger key. The upper end of the key stem 35, connected with the shift lever 29, is connected with a shift key 36 inscribed with suitable indices such as "capitals," whereas the other shift key 37, which 110 is connected to the shift lever 30, is inscribed with suitable indices, such as "figures." The shift key lever 30 has one end of a contractile spring 38 connected thereto, the opposite end of said spring being connected at 39 to a side plate of the frame. 115

One of the depending arms 28 of the shift frame is provided with a laterally projecting lug or stop 40 which is adapted to co-operate with screw stops 41 and 42 to limit 120 the movements of the case shift rail or frame, and the parts carried thereby, to and away from normal position. The screw stops 41 and 42 are received in and extend through tapped openings in rearwardly projecting arms 43 and 44, respectively, of a bracket 45 secured by screws 46 to the cross bar 4.

Each of the parallel guide links 25 is extended rearwardly beyond its pivot 26 to 125

form rearwardly extending parallel arms 47 which are united at their rear ends by a tie rod 48. The links 25 are therefore rigidly connected to move together so that movement transmitted to the shift bar or frame at one side of the machine is transmitted to both shift links or arms 25.

It will be understood that a depression of the "figure" shift key 37 is effective to produce a case shifting movement of the platen in order to bring it to a position where the outermost types of the bars will impact at the printing point, the stops 40 and 42 cooperating to arrest the parts in this shifted position. Should, however, the operator desire to write a "capital," or other upper case character carried by the middle types on the bars, it will be necessary to depress the "capital" shift key 36. This depression is effective to elevate the rear end of the lever 29 and move the shift rail and the parts carried thereby upwardly to the position shown in Fig. 4. However, the case shifting movement of the platen is interrupted when it reaches a position where a middle type on each bar is adapted to impact at the printing point by an automatically controlled device. Thus, from an inspection of Figs. 1 and 4, it will be seen that an arresting member, designated as a whole by the reference numeral 49, is pivoted on a shouldered pivot screw 50 to the frame of the machine. This arresting member is slotted at 51 to receive a laterally projecting pin 52 which extends from one side of a depending ear on the shift lever 29, forming a pin and slot connection between said shift lever and the arresting device 49. A depression of the shift key 36 is effective to move the arresting member 49 so that the hook-like end 53 thereof will be interposed in the path of the pin 33 and against the bottom of which pin the rear end of the lever 29 bears to effect an upward case shifting movement of the platen. The parts are so timed that the part 53 of the arresting device will be interposed in the path of the pin 33 at a time when the platen is in position to receive the impact of the middle type on each bar, and when the lug 40 reaches about midway between the screw stops 41 and 42, the former of which limits the extreme upward case-shifting movement of the platen. An upward pressure on the pin 33, exerted by depressing the finger key 36, is therefore resisted by the arresting device 49, controlled by the shift lever 29. Upward pressure directed on the member 49 is resisted by the pivot 50 of said device so that the construction is such as to hold the platen against vibration. When finger pressure is released on the shift key 36 the arresting device 49 and the shift lever 29 will be returned to normal position by a contractile spring 54, connected at one end 55 to the

arresting member and at its opposite end 56 to a pin which projects from the frame of the machine.

In order to provide spring means to counterbalance or partly compensate for the weight of the shift rail and carriage, I have extended one of the parallel links 22 downwardly beyond its pivot to provide a crank arm 57 as shown in Fig. 6. A bent link 58 is pivoted at its rear end, as at 59, to the depending crank arm 57. The opposite end of this link is connected to one end of a contractile spring 60, the opposite end of which is connected at 61 to an angular projection on a bracket plate 62 which is riveted at 63 to a side plate of the frame. The power of the spring, therefore, is exerted through the member 52—22, to counterbalance, or partly compensate for, the weight of the carriage and the case shift rail or frame in order to enable the parts to be shifted by exerting but a comparatively light pressure on the shift keys.

In order to lock the platen in either of the two positions shown in Figs. 3 and 4, to which it may be shifted from the normal position, I have provided a locking device, designated as a whole by the reference numeral 64. This device is pivoted to a side plate of the machine by a shouldered pivot screw 65 and is provided at one end with a finger piece 66 by which it may be controlled. A depending arm of this device carries a laterally projecting pin 67 which, when the parts are in the normal position, is arranged forward of two upwardly and forwardly extending projections 68 and 69 on the shift key levers 29 and 30, respectively. When, however, either of the shift keys 36 or 37 is depressed, the parts controlled thereby may be locked in the shifted position by moving the finger piece 66 upwardly to bring the pin 67 above the depressed projection 68 or 69, and thus lock the actuated shift lever and the parts controlled thereby against return movement. When the locking member 64 is again moved to the normal position shown in Fig. 1, the shift lever which has been maintained locked by the device 64 will be released and the parts will return to normal position.

In order to maintain the locking device 64 against accidental displacement from either of the two positions to which it may be moved and to limit the pivotal movements of said locking device, I have provided a strap 70 which is fixed at one end by screws 71 to a side plate of the frame. This strap is bent at 72 and at its free end thus partly surrounds the arm of the locking device 64 which carries the finger piece 66. The strap 70 is in the nature of a spring arm provided with a slight projection 73 made by an indenture in the spring metal from which the strap is formed. The projection 73 is

adapted to bear against the side of the locking device with sufficient pressure to maintain it against accidental displacement from either of the two positions on which it may be turned on its pivot.

- In the present construction the carriage is shown controlled in its step-by-step letter space feed movement by a feed rack 74 fixed to the guide bar 14 of the carriage by screws 75. Feed dogs 76 and 77 coöperate with the feed rack to control the step-by-step movement of the carriage. These feed dogs are carried by a dog rocker 78 which is pivoted at 79 in ears 80 which project from a bracket 15 plate, the latter being fixedly connected to the shift rail or frame 18. Movement is transmitted to the dog rocker by an actuating member 81 which coöperates at its rear edge 82 with a laterally projecting arm 83 on 20 the dog rocker. The actuating member 81 is supported on the frame of the machine by links (not shown). An arm 84 extends forwardly from the actuating member 81 and is connected to a segmental universal bar 85. 25 The universal bar extends in the path of the type bars in their movements to the printing position, the forward edge of each type bar contacting near the heel thereof with the front edge of the universal bar to operate 30 the actuating member 81 and the dog rocker. It will be seen that while the actuating member 81 is carried by the frame of the machine, the escapement mechanism comprising the dog rocker, the feed dogs carried 35 thereby and the feed rack are shiftable with the carriage during the case shifting movements of the latter, the escapement mechanism being carried in part by the carriage and in part by the shift rail.
- 40 From an inspection of Fig. 5 it will be seen that the platen 11 in its case shifting movements receives at the printing point a straight line movement on the line *a*, said line extending through a pivot 6 of a type bar. It will be seen, moreover, that lines *b* and *c* drawn through the axis of the platen and through the printing point are perpendicular to the line of shift represented by the line *a*. It will also be seen that the line 45 *d* which extends through the printing point and substantially through the axis of the platen, when the platen is in a position to receive the impact of the middle types on the bars, is substantially perpendicular to the line of shift indicated by the line *a*. The extent of deviation from the perpendicular of this line is represented in Fig. 5, although the figure being drawn on a very much enlarged scale exaggerates the extent of deviation from what it would actually be in practice. From this diagram it will be understood that the two end types on each bar strike squarely "on their feet" at the printing point, whereas the center type for each 55 bar is slightly "off its feet" to an extent rep-

resented by the deviation of the line *d* from the axis of the platen in the middle position of the latter. This deviation is so slight that in practice no attempt need be made to take care of it in the manufacture of the types, it 70 being found practicable for manufacturing purposes to make the types with all three printing faces on each bar in the same plane, as indicated by the line *e* in Fig. 7. When I speak of the printing faces of all three types 75 on each bar being in the same plane I disregard the fact that there is a slight curvature in the face of each type to match the platen. Disregarding this curvature the printing faces of all three type on the bar may be 80 regarded as in the same plane.

If preferred, the types may be manufactured so that the plane of the printing face of the middle type on each bar is different from that of the end types so as to compensate for and correct said middle types to the extent that they are "off their feet." However, it is believed that this will be found unnecessary.

In view of the fact that each pivoted type bar has the same extent of angular movement to the printing position irrespective of the case position to which the platen may be shifted, the printing faces of all of the types will be formed in a like manner, and the printing faces of all three type on each bar may be in the same plane. But even if it be found desirable to alter the plane of the printing face of the middle type on each bar with reference to the plane of the printing faces of the other two types, this would be an easy manufacturing expedient since the angular relation between the type faces on all of the bars would be the same throughout the system.

105 It will be understood that in accordance with the present invention the guide links of the shift mechanism are so disposed and proportioned as alone to guide the platen so that the axis thereof shifts in a straight 110 line; that the pivots of the type bars are disposed in a plane parallel to the line of shift of the axis of the platen, so that each type bar has the same angular movement in the printing operation for each type thereon in 115 all case positions of the platen; that as shown the line of shift of the axis of the platen is at an angle to a vertical plane passing through the axis of the platen when the latter is in the normal position; that the axis 120 of the platen and the printing point shift in parallel planes; that the printing faces of the types on each bar when in the printing position are parallel with the plane of shifting movement of the axis of the platen 125 in all case positions of the platen; that the fixed pivots on which the lower set of guide links turn are at the rear ends of said links and in a plane forward of the fixed pivots of the upper links; and that the forward 130

end of each of the lower guide links is connected to the platen carrier at a point in the rear of the point of connection of its associate upper link.

5 The construction of my present invention is such that a simple and effective linkage is provided, whereby a straight line movement of the platen at the printing point is provided, and whereby the types may be made 10 with the printing faces of all three types on each bar in the same plane, or substantially in the same plane, and whereby the type bars have the same extent of angular movement to the printing position in all three 15 case positions of the platen. These features enable me to provide a typewriting machine which may be manufactured at small cost, which is simple in construction and operation and efficient in use.

20 Certain of the features herein shown and described relating to the carriage mounting are not claimed *per se* herein but form the subject-matter of an application filed by me August 4th, 1913, Serial No. 782,859.

25 Various changes may be made without departing from the spirit and scope of my invention.

What I claim as new and desire to secure by Letters Patent, is:—

30 1. In a typewriting machine, the combination of printing instrumentalities, a platen, means for shifting the platen from normal position to either of two other printing positions at will, and arresting means comprising 35 two fixed stops, a movable stop connected with the shift mechanism and adapted to move from one of said fixed stops to the other, a key controlled stop, and a part on the shift mechanism adapted to coöperate 40 with said key controlled stop to arrest the platen at a point in advance of that which it is arrested by the coöperation of one of the first mentioned fixed stops and its co-acting movable stop.

45 2. In a typewriting machine, the combination of printing instrumentalities, a platen, a shift frame therefor, a stop on the latter, two fixed stops for said shift stop, two additional stops one on the shift frame and the 50 other movably mounted on the main frame, and means for actuating said shift frame.

55 3. In a typewriting machine, the combination of printing instrumentalities, a platen, a shift frame therefor, a stop on the latter, two fixed stops for said shift stop, two additional stops one on the shift frame and the other movably mounted on the main frame, two key levers adapted to move the shift frame, one set of stops coöperative when 60 one of said key levers is actuated and the other set coöperative when the other of said key levers is actuated.

65 4. In a typewriting machine, the combination of a series of type bars each carrying three types, a platen, and means for causing

relative shifts between said type bars and platen, said means comprising a shift frame, two independent levers for actuating said shift frame, one set of stops to arrest the shifted member when one of said key levers 70 is actuated, and another set of stops to arrest the shifting member at a different point when the other of said key levers is actuated.

5 In a typewriting machine, the combination of a series of type bars each carrying 75 three types, a platen, and means for causing relative shifts between said type bars and platen, said means comprising a shift frame, two independent levers for actuating said shift frame, a part on said shift frame with 80 which the rear end of each of said levers engages to actuate said shift frame, a set of stops for determining the amount of movement of said shift frame when one of said levers is operated and an independent set of 85 stops for determining the amount of movement of the said shift frame when the other of said levers is operated.

6. In a typewriting machine, the combination of a series of type bars each carrying 90 three types, a platen, and means for causing relative shifts between said type bars and platen, said means comprising a shift frame, two independent levers for actuating said shift frame, a part on said shift frame 95 with which the rear ends of said levers engage, a stop on said shift frame, a fixed stop against which the shift frame normally rests, a second fixed stop with which the shift frame stop co-acts when the shift frame is 100 moved a double distance or the distance between two extreme types on a type bar, and a movable stop connected to one of the key levers and adapted to be moved into the path 105 of a part on the shift frame when said lever is actuated, whereby the shift frame is arrested at a single distance position for the printing of the middle types on said type bars.

7. In a typewriting machine, the combination of a series of type bars each carrying three types, a platen, and means for causing relative shifts between said type bars and platen, said means comprising a shift frame, two independent key levers of the first order, 110 both adapted to engage a stud on said shift frame, one of said levers being adapted to move the shift frame a double distance, the other to move the shift frame a single distance, a fixed stop and a movable stop for arresting the shift frame when moved one of said distances, and a key controlled movable stop for engaging the stud on the shift frame to arrest the latter when moved to the other of said distances.

115 8. In a typewriting machine, the combination of a series of type bars each carrying three types, a platen, and means for causing relative shifts between said type bars and platen, said means comprising a shift frame, 120

a pair of independently pivoted key levers of the first order, the rear ends of which both engage a stud on said shift frame, a movable stop on said shift frame, a fixed stop against which said movable stop rests in the lower case printing position of the parts, another fixed stop against which said movable stop strikes when the shift frame is moved its greatest distance or that between the extreme types on said type bars, a hook pivotally attached to a fixed part of the machine and operatively connected to one of said key levers and adapted when said key lever is actuated to be interposed in the path of travel of said stud, whereby the shift frame is arrested at a midway position for the printing of capitals and at which time the first mentioned movable stop stands at a place intermediate the aforesaid two fixed stops.

9. In a typewriting machine, the combination

of a platen carrier, a cylindrical platen, two sets of links relatively so disposed and proportioned as alone to guide the platen so that the center thereof shifts at an angle to a vertical plane passing through said center in normal position, a series of upwardly and rearwardly striking pivoted type bars having each three types, the pivots of said type bars being disposed in a plane parallel with the plane of shift of the center of the platen, whereby each type bar has the same angular movement in the printing operation for each type thereon in all case positions of the platen.

Signed at Syracuse, in the county of Onondaga, and State of New York, this 22d day of September, A. D. 1913.

ARTHUR J. BRIGGS.
